UNITED STATES PATENT OFFICE.

OTTO VOGEL, OF BERLIN, GERMANY, ASSIGNOR TO SIGMUND LUDWIG GOLDMAN, OF LONDON, ENGLAND.

BOTTLE OR SIMILAR WASHING APPARATUS.

No. 821,005.

Specification of Letters Patent.

Patented May 22, 1906.

Application filed January 30, 1905. Serial No. 243,242.

To all whom it may concern:

Be it known that I, OTTO VOGEL, a subject of the Emperor of Germany, residing at Berlin, Germany, have invented certain new and useful Improvements in Bottle or Similar Washing Apparatus, of which the following is a specification.

This invention relates to bottle or similar washing apparatus, and has particular reference to that type of machine in which an intermittently-operating jet or spray device is employed for washing the interior and a part or the whole of the exterior of each bottle or other vessel while in an inverted position. In addition to the intermittently-operating jets a continuously-operating spray device is preferably provided in such machines by which water is discharged upon the inverted ends of the bottles; and the object of the present invention is to provide a machine of this type which shall be more efficient than those heretofore invented.

In the accompanying drawings, which illustrate one method of carrying out this invention as applied, by way of example, to the washing of bottles in particular, Figure 1 is a plan of the apparatus. Fig. 2 is a section of the same on the line 2 2. Fig. 3 shows the right-hand top portion of Fig. 2 on an enlarged scale. Fig. 4 is an end view of Fig. 3 with the outer casing removed. Fig. 5 is a section of a part of Fig. 1 on the line 5 5. Fig. 6 is a sectional plan on the line 6 6 of Fig. 2. Fig. 7 is a perspective view in part section of a detail of Fig. 2, shown on an enlarged scale. Fig. 8 is an elevation of a modified detail. Fig. 9 is an end view of the same. Fig. 10 is a central vertical section through the pump shown in Fig. 2, and Fig. 11 is a transverse section of the same on the line 11 11 of Fig. 10.

Like letters of reference indicate like parts throughout the drawings.

The apparatus comprises a circular revolving tray A, carried upon a central support B. The under side of the tray A is dished and has secured to it a disk A', dished at its center and having a central boss A'', forming a bearing-surface by which the whole can be rotatably carried. The connection between the members A A' is made water-tight, so that the inclosed space constitutes a chamber by

which water can be supplied to a series of tubes or jet-nozzles C C', carried by the tray A and opening into the chamber beneath it. 55 The boss A'' is conically bored on its interior and constitutes a shell which takes over a hollow plug or cock B', carried by the pedestal B. The cock has a series of perforations B'', and the shell is provided with a corresponding series of perforations A'', which open into the chamber formed between the parts A A'.

Beneath the disk A' is a basin-like receptacle D, carried by suitable supports D'. The outer wall of this receptacle extends above 65 the plate A' and carries a circular casing E, which supports a cover E'. The cover is hollowed on its under side and the hollow portion closed in by a plate E'', having perforations E''', and extending from the hollow cock B' is 70 a conduit E', which passes through the perforated plate E'' and communicates with the space between the cover and this plate.

An opening is provided in the casing E and cover E', as shown, and depending from the 75 cover at each edge F of the opening is a series of brushes G. These brushes are conveniently disposed radially to the center about which the tray A turns, so that the space formed between them is wedge-shaped, as 80 clearly shown in Fig. 1.

Secured beneath the tray A is an arm H, carrying a plate H', disposed beneath the cut-away portion F and shaped to correspond thereto. The arm H is rigidly secured by 85 any convenient means to the cock B', and the plate H' is carried thereon by pins H'', surrounded with spiral springs H''', Fig. 7. The pins H'' are free to slide in the arm H, so that the springs maintain the plate H' 90 against the under side of the tray A.

The upper portion of the central support B is hollow and communicates at one end with the interior of the cock B' and at the other end with a conduit J. The free end of the 95 conduit J enters a receptacle D'', Figs. 1 and 5, at the side of the basin-like receptacle D and communicating therewith. At the upper end of the conduit J is a strainer J', and the receptacle D'' is provided with a hinged 100 lid D'', which may be raised for the purpose of lifting the strainer J' out of its seating, so that it may be cleansed without stopping the whole process of washing. An overflow-

pipe J^2 also communicates with the receptacle D .

The disk A' carries a dependent flange K , to which is secured a toothed wheel K' , by which the tray is rotated. The wheel K' gears with a pinion K^2 on a spindle K^3 , free to rotate in a bracket L , conveniently secured to one of the supports D' . The spindle K^3 also carries a worm-wheel K^4 , driven by a worm K^5 on the shaft K^6 . The shaft rotates in bearings K^7 , also secured to the bracket L , and is further supported by a second bracket K^8 , secured to one of the other supports D' . The shaft K^6 carries a pulley K^9 , by which it may be driven from any convenient source of power.

On the shaft K^6 is also a crank-disk M , connected by a pin M' and link M^2 to a pin N' , carried by a movable portion of the pump N . The pump comprises two cylinders inverted one in the other; the outer cylinder being movable. Mounted in the inner cylinder is a non-return valve N^3 , by which water passes from the pipe J into the pump, and a second non-return valve N^4 permits the water to be discharged into the hollow column B by a pipe J^3 . The non-return valves may be spring or otherwise controlled; but it will be understood that the pump forms no part of the present invention and may be constructed as convenient.

The operation of this apparatus is as follows: Water is first supplied to the interior of the standard B and cock B' from any suitable source of supply, which may communicate with the conduit J at a point between that at which the pump is interposed and the standard B . Water passes up the conduit E^4 to the cover E' , whence it falls through the perforations E^3 onto the tray A . As the tray is rotated by the driving mechanism described the bottles O are placed in an inverted position over the jet-nozzles $C C'$ as they pass the open space F . The outlets in the jet-nozzles $C C'$ may be disposed in any suitable manner; but the discharge from them is intermittent, as water will only flow to them from the cock B' when the orifices B^2 therein coincide with the orifices A^3 in the shell or boss A^2 . The water-supply is, however, cut off from the nozzles $C C'$ while within the space F by the plate H' , which closes the nozzles at this point.

After the bottles have been carried round by the tray A , during the whole of which time they are intermittently syringed by the jet-nozzles $C C'$ and continuously sprayed from the cover E' , they are delivered again into the open space F after passing under the elastic wall formed by the brushes G . These brushes are made sufficiently long to sweep the bottoms of the bottles, so that they serve the double purpose of, first, preventing the

sprayed water from flying into the space F to the inconvenience of the operator, and, second, wiping out the water collected in the hollow bottoms of the bottles as they are discharged into the space F , as shown in Fig. 4.

Various materials may be used in place of the brushes G , such as rubber or other pendant strips G' ; but the brushes are preferred, as in addition to acting as a screen they discharge the water from the bottoms of the bottles, as described.

The water sprayed upon the bottles collects in the chamber D and flows thence into the pipe J . Preferably it is returned from the pipe J to the hollow support B by the pump N ; but, if preferred, it may be allowed to run to waste. It will be understood that whether the water is returned by the pump or whether a fresh supply is constantly employed it must be under sufficient pressure to rise to the cover E' and to spray from the jet-nozzles $C C'$ with the required force. The overflow-pipe J^2 carries away any surplus supply of water should this not be drawn away sufficiently quickly from the chamber D by the pump.

It will be understood that the operator replaces the washed bottles by those that are unwashed as each part of the tray passes the space F .

It will be seen that the tray $A A'$ need not be built up in the particular manner shown so long as a tray having a hollow interior, with which the open ends of the jet-nozzles $C C'$ can communicate, is provided. Similarly the cover E' may be built up in any suitable manner so long as a hollow interior is formed to which the liquid can be supplied.

What I claim as my invention, and desire to secure by Letters Patent, is—

1. In apparatus for washing hollow vessels the combination of a hollow tray to carry the vessels, means for supporting the tray, means for rotating the same about a vertical axis, a series of jet-nozzles for liquid directed against the vessels and communicating with the hollow interior of the tray by which latter they are carried, means for supplying liquid to the interior of the tray, a plate within the tray bearing against the ends of the nozzles at the point where they communicate with the hollow interior so that it closes a given number of them according to the dimensions of the plate, and means for holding the plate against rotation with the tray, substantially as set forth.

2. In apparatus for washing hollow vessels the combination of a hollow tray to carry several rows of the vessels in an inverted position, a series of jet-nozzles for liquid directed against the vessels and communicating with the hollow interior of the tray by which latter they are carried, means for supplying

liquid to the interior of the tray, means for rotating the tray, an annular casing surrounding the same, a stationary support for the casing, a spray device at the top of the casing for discharging liquid down upon the inverted ends of the several rows of vessels, a plate within the tray bearing against the ends of the nozzles at the point where they communicate with the hollow interior of the same thus closing a given number of them according to the dimensions of the plate and such plate being further situated opposite an opening in the casing, and means for holding the plate against rotation with the tray, substantially as and for the purpose described.

3. In apparatus for washing hollow vessels the combination of a hollow tray to carry several rows of the vessels in an inverted position, a series of jet-nozzles for liquid directed against the vessels and communicating with the hollow interior of the tray by which latter they are carried, means for supplying liquid to the interior of the tray, means for rotating the tray, an annular casing surrounding the same having an opening therein, a stationary support for the casing, a spray device at the top of the casing for discharging liquid down upon the inverted ends of the several rows of vessels, a plate within the tray bearing against the ends of the nozzles at the point where they communicate with the hollow interior of the same thus closing a given number of them according to the dimensions of the plate, such plate being further situated opposite an opening in the casing, means for holding the plate against rotation with the tray, a support extending toward the interior of the casing from a point approximately at the top of one of the outer edges of the opening in the same, a second support similarly extending from the opposite edge of the opening, and an elastic wall pendent one from each of the supports the lower edge of each sweeping upon the inverted ends of the several series of vessels on the tray as they pass substantially as set forth.

4. In apparatus for washing hollow vessels the combination of a hollow tray to carry several rows of the vessels in an inverted position, a series of jet-nozzles for liquid directed against the vessels and communicating with the hollow interior of the tray by which latter they are carried, means for supplying liquid to the interior of the tray, means for rotating the tray, an annular casing surrounding the same, a stationary support for the casing, a spray device at the top of the casing for discharging liquid down upon the inverted ends of the several rows of vessels, a plate within the tray bearing against the ends of the nozzles at the point where they communicate with the hollow interior of the same thus closing a given number of them accord-

ing to the dimensions of the plate, such plate being further situated opposite an opening in the casing, means for holding the plate against rotation with the tray, a support extending from a point approximately at the top of one of the edges of the opening in the casing toward the interior of the same, a second support similarly extending from the opposite edge of the opening and a series of brushes pendent from each support the lower edges of the brushes sweeping upon the inverted vessels on the tray as they pass, substantially as set forth.

5. In apparatus for washing hollow vessels the combination of a hollow tray to carry several rows of the vessels in an inverted position, a series of jet-nozzles for liquid directed against the vessels, and communicating with the hollow interior of the tray by which they are carried, means for supplying liquid to the interior of the tray, means for rotating the tray, an annular casing surrounding the same, a stationary support for the casing, a hollow cover to the casing having perforations in the under side thereof, means for supplying liquid to the hollow interior thereof, a plate within the tray bearing against the ends of the nozzles at the point where they communicate with the hollow interior of the same thus closing a given number of them according to the dimensions of the plate, such plate being further situated opposite an opening in the casing, means for holding the plate against rotation with the tray, and elastic walls depending from the cover one extending from each side of the opening in the casing toward the interior of the same, substantially as set forth.

6. In apparatus for washing hollow vessels the combination of a hollow tray to carry a series of the vessels in an inverted position, a series of jet-nozzles for liquid directed against the vessels and communicating with the hollow interior of the tray by which latter they are carried, means for supplying liquid to the interior of the tray, means for rotating the tray, an annular casing surrounding the same, a stationary support for the casing, a spray device at the top of the casing for discharging liquid down upon the inverted ends of the several series of vessels, a plate within the tray bearing against the ends of the nozzles at the point where they communicate with the hollow interior of the same thus closing a given number of them according to the dimensions of the plate such plate being further situated opposite an opening in the casing, means for holding the plate against rotation with the tray, a support extending from a point approximately at the top of one of the edges of the opening in the casing toward the interior of the same and situated vertically above one edge of the plate within

the tray, a second support similarly extending from the opposite edge of the opening and situated vertically above the other edge of the plate within the tray, and an elastic wall pendent from each support the lower edges of which sweep upon the inverted ends of the vessels on the tray as they pass, substantially as set forth.

In testimony whereof I have signed my name to this specification in the presence of 10 two subscribing witnesses.

OTTO VOGEL.
